UNITED STATES PATENT OFFICE.

FRANK MULIG, OF GREENDALE, OHIO.

MEMORANDUM-CALENDAR.

1,219,987.

Specification of Letters Patent. Patented Mar. 20, 1917.

Application filed February 25, 1916. Serial No. 80,470.

To all whom it may concern:

Be it known that I, FRANK MULIG, a citizen of the United States, residing at Greendale, in the county of Hocking and State of Ohio, have invented new and useful Improvements in Memorandum-Calendars, of which the following is a specification.

This invention relates to improvements in calendars, and particularly to calendars 10 of the perpetual type, embodying means for keeping desired memoranda, the object of the invention being to provide a calendar including a face plate bearing thereon fixed calendar matter, adapted for coöperation 15 with a pointer and a removable calendar leaf, by which a calendar covering any month of any year may be produced.

A further object of the invention is to provide a calendar having a compartment to 20 receive a current removable calendar leaf or sheet and another compartment to receive leaves or sheets of back periods for future reference, together with means for indicating upon the sheet, in a manner visible through the face plate, memoranda pertaining to accounts, etc., whereby an accurate record may be kept of all household or 25 other expenditures during the current month, the totals calculated at the end of the month, and a record kept of all transactions of such character from month to month in a ready and convenient manner.

A still further object of the invention is to provide a calendar which, with the use of 30 removable and interchangeable sheets, is adapted for perpetual use, which may also be employed as an advertising medium, if desired.

The invention consists of the features of 35 construction, combination and arrangement of parts hereinafter fully described and claimed, reference being had to the accompanying drawings in which:

Figure 1 is a front view of a memorandum calendar constructed in accordance with my invention.

Fig. 2 is a vertical longitudinal section on line 2—2 of Fig. 1.

Fig. 3 is a horizontal transverse section on line 3—3 of Fig. 1.

Fig. 4 is a face view of one of the calendar sheets with its backing detached.

Fig. 5 is a view of the sheet in an outspread or unfolded condition.

Referring to the drawings, 1 designates a

frame of suitable form and construction and made of any suitable material. In the present instance the frame is shown as being of oblong rectangular form, and provided at its upper portion with a calendar casing 2, below which is a space or panel 3 in which may be printed or otherwise exposed directions for using the calendar, etc. If desired, a space 4 may be arranged below the space 3 to receive a picture, mirror or other suitable pictorial or ornamental matter or article of utility. Below this space 4 may be provided a space 5 to receive advertising or other matter.

The casing 2 comprises a front or face plate 6, a back or rear wall 7, side walls 8, and a bottom wall 9, said casing being open at the top and subdivided by a transverse partition 10 into a front chamber or compartment 11 and a rear chamber or compartment 12. The back 7 is preferably provided with a short upward extension having an opening 13 formed therein, whereby the device may be supported upon a wall from a nail or other suitable hanger.

The front or face plate 6 is provided with a central panel or dial portion 14, which is of circular form, and has arranged therein a pivoted dial or pointer 15, which is adapted to sweep around the surface thereof. 85 This dial or pointer is adapted for coöperation with a circular space or field 16 surrounding the dial and provided with radial divisions corresponding in number to the number of days in a long month, the numbers from 1 to 31 inclusive, being arranged in regular and consecutive order within the divisions of said space and around the circumference of the dial. Upon the dial, or some other suitable portion of the face plate, appears a table of the months of the year, together with a statement of the number of days in each month of an ordinary year. The hand 15 is intended to be adjusted from day to day into registry with the day 95 numeral of the current month, which is designed to appear upon a removable calendar sheet or leaf and to be exposed through an observation slot or opening 17 in the face plate. At a suitable point upon the face plate is a holder 18 for a pencil, pen or like writing instrument, for the convenience of the user in making memoranda, as herein-after fully described.

Formed within the face plate 6 concen-

trically with relation to each other and to the space 16, are other inner and outer annular spaces 19 and 20 provided with radial divisions coinciding with the radial divisions of the month numeral spaces, said divisions being cut out in the form of slots or openings, as shown. At a point above the dial and annular spaces above mentioned, the face plate is also provided with a transverse series of slots or openings 21, nine in number in the present instance, above which at the top of the face plate, are numerals designating certain values or indications, the numerals being arranged above and in alignment with the slots 21 and consisting in the present instance of the numerals 1, 2, 3, 4, 5, 10, 15, 20 and 25, which, for convenience of illustration and description, may represent certain monetary values, as cents or fractions of a dollar. Above this the face plate may be provided with a finger recess 22 for the purpose of exposing the upper edge of the calendar and memorandum sheet and its backing.

25 The calendar and memorandum sheet 23 is designed to have its active portion exposed through the slots in the face plate so as to indicate matter which may be written or printed thereon, and at the same time 30 to permit matter to be written or impressed thereon by means of a pencil or other instrument inserted and brought into contact therewith through the aforesaid slots in the face plate. Each sheet is preferably of double the dimensions of the face plate and is folded to provide leaves 24 and 25, formed by folding the sheet along a central transverse line upon itself. This sheet is preferably used in connection with a backing 26, 40 composed of cardboard or other suitably stiff material, which is disposed between the leaves of the sheet, the free edges of which are held in proper position by a clip or other fastening 27. By this arrangement the leaf 45 24 may first be exposed and used, and the sheet then reversed and the leaf 25 used, and if desired the opposite surface of the sheet may be employed in like manner, thus giving from 2 to 4 calendar leaves or pages 50 upon each sheet, each designed to represent and to be used during the current month period of a year.

It will be evident that when a sheet is arranged in position for use, with the current 55 month and year marked thereon so as to be visible through the slot 17, a calendar for the current month is produced, and that the days during this period may be indicated by adjusting the pointer 15. At the end 60 of this month's period, another leaf may be brought into position with the new month marked thereon, and after one sheet has been used it may be detached from the backing and another employed in its place, and 65 the used sheet transferred from the front

compartment 11 to the back compartment 12 in which it may be stored with other used leaves for future reference.

The object of providing the slots in the face of the calendar is to enable data to be marked upon the current calendar leaf for the purpose of keeping a record of financial or other transactions and it will be understood that through the slots 19 in line with any of the day numerals matter may be marked upon the leaf 24 indicating an obligation which should be met on that day, and through the registering slot 20 the leaf 24 marked to indicate that said obligation was met, or in these spaces may be marked items of the total of debts contracted during a certain day, while through the spaces 20 may be marked items pertaining to amounts paid out on the same day, etc. The slots or openings 21 are provided for 85 indicating minor items of expenditures leading to the sum totals, and which may be indicated upon the exposed leaf of the calendar sheet by dots or other indications, the dots under the numeral 1 indicating cents, 90 those under the numeral 5 five cents, and those under the numeral 25 twenty-five cents each, as will be readily understood, and at the end of the month period these items may be totalized and the totals set 95 down at the bottom of the exposed spaces, so that at the end of the month the totals of obligations and expenditures may be readily and conveniently found and properly indicated upon the sheet, so that the 100 user of the calendar may have an accurate record, which may be preserved for future use, of his household or other expenses for the period of any month of a current year. After each sheet is used the sheets will be 105 transferred to the rear compartment 12, so that a record of all the accounts, itemized by day, may be kept for reference at any future time.

It will thus be seen that the invention provides a calendar which embodies indicating means adapted for use in connection with removable sheets to provide a perpetual calendar, and which is also adapted for memorandum purposes in the ready and convenient manner set forth, whereby an article of this character of maximum value is produced.

I claim:—

1. A calendar comprising a casing having a receiving compartment and a dial forming the front of said compartment and provided with an annular series of radially arranged month designations, and a plurality of series of slots arranged beyond 125 said designations and concentric therewith, and provided also with a transverse opening, and a combined calendar and memorandum sheet adapted to be disposed within said compartment and exposed through said 130

slots, whereby appropriate matter may be displayed through the transverse slot and matter written thereon through the concentric slots pertinent to said month day 5 designations, and an indicator upon the face of the dial coöperating with said month day designations.

2. A calendar of the character described comprising a casing forming front and rear 10 compartments, the front wall of the front compartment forming a dial and being provided with an annular series of radial month day designations, and a plurality of 15 annular series of slots outside of said month day designations and concentric therewith, and further having a horizontal transverse slot at the top of said dial, a hand or pointer

upon the dial adapted for coöperation with said month day designations, a backing sheet adapted to fit within the front compartment, and a combined calendar and memorandum sheet folded to embrace said backing sheet and provided with front and rear portions detachably fastened thereto, the front sheet portion being arranged so as 20 to be displayed through said slots in the dial.

In testimony whereof I affix my signature in presence of two witnesses.

FRANK MULIG.
